UNITED STATES PATENT OFFICE.

JOHN WILLIAM BENNETT, OF HALIFAX, NOVA SCOTIA, CANADA, ASSIGNOR
TO CHARLES HENRY BENNETT, OF SAME PLACE.

STENCIL-HOLDER.

SPECIFICATION forming part of Letters Patent No. 277,201, dated May 8, 1883.

Application filed October 9, 1882. (Model.)

To all whom it may concern:

Be it known that I, JOHN W. BENNETT, of 5
Halifax, in the Province of Nova Scotia and
Dominion of Canada, have invented a new
and Improved Stencil-Holder, of which the
following is a full, clear, and exact description.

The object of my invention is to provide a
device adapted for conveniently holding sten- 10
cil-plates, so as to allow of their being inserted
and removed to form any particular name or
address, as may be required; also for holding
permanent stencil-plates of any form or shape.

The invention consists in a holder composed
of two slotted clamping-plates, between which
15 the letters are held so as to be flush with the
lower face of the bottom plate, and provided
with a handle, as hereinafter described and
claimed.

Reference is to be had to the accompanying
20 drawings, forming a part of this specification,
in which similar letters of reference indicate
corresponding parts in both the figures.

Figure 1 is a perspective view of my im-
proved stencil-holder with a part broken out.
25 Fig. 2 is a cross-section of the same.

A B are two plates, preferably made of metal
of suitable length and width, and provided
with one or more longitudinal slots, *a a*, of
the shape and form required. These plates
30 are provided with flanges *c* at their ends, and
the upper plate, A, is made slightly shorter
than the lower plate, B, so that it will set
closely down thereon. If made of thin sheet
metal, the upper plate may be strengthened by
35 strips or flanges *d* along the edges of its slot.
The flanges *c* of the upper plate, A, are ex-
tended upward to receive the handle D, which
serves as a convenient means for holding the
device. The upper plate is also provided with
40 lugs *f* at its ends, which extend through slots
formed in the flange *c* of the lower plate, and
serve as a means for guiding and retaining the
upper plate. Upon the side flanges of the up-
per plate are springs *g*, which are formed at
45 their lower ends with pins *h*, for entering holes
i, formed in the flanges *c* of the two plates,
for retaining the plates in either position—
that is to say, separated, as shown in Fig. 1,
or when moved together to clamp the stencil-

plate. The stencil-plates shown at *k* have their 50
ends bent or offset, so that when they are
placed upon the lower plate the ends will rest
upon the same at the sides of the slot, while
the middle portion, having upon it the letter,
projects downward into the slot, so as to be 55
flush with the bottom of the plate B.

In using the holder the upper ends of the
springs *g* are to be pressed inward, thereby
disengaging the pins *h*, and allowing the lower
plate to drop down the distance allowed by 60
the lugs *f*. The stencil-plates can then be in-
serted in the proper order, after which the
two plates are to be brought together, so as
to clamp the stencil-plates, in which position
the plates A B are held by the pins *h*. The 65
stencil can now be used, the slot in the upper
plate, A, allowing of the brush being passed
over the plate. Usually there will be two slots
a in the plates for two rows of stencil-plates,
so that both the name and address may be set 70
up, and in that case the handle will come be-
tween the two slots, so that they are easily
accessible; but in case there should be only
one slot the flanges *c* may be bent at one side,
so that the handle shall not be in the way. 75
This holder serves to retain the stencil-plates
firmly clamped, so that there is no risk of their
bending or buckling up.

The holder may be made of any suitable mate-
rial and in any desired form. When constructed 80
for holding permanently a stencil-plate of any
form, size, or character—such as are used for
marking barrel-heads—the plates A B are to
be made of the same form and size as the sten-
cil, and made with straight, curved, diamond, or 85
other shaped slot, as may be required. The
upper plate, A, is to be secured upon the lower
one by screws or similar devices, the end
flanges and other parts shown not being re-
quired. The stencil-plate will thus be held in 90
a firm and substantial manner, so that it will
be much more durable and lasting, besides
being more convenient for use.

Having thus described my invention, I claim
as new and desire to secure by Letters Patent— 95

1. In a stencil-holder, the combination of
two correspondingly-slotted plates, A B, hav-
ing upwardly-projecting end flanges, *c*, the

plate A being shorter than and fitting between the flanges of plate B, as shown and described.

2. In stencil-holders, the combination of the two slotted plates A B, provided with end flanges, *c*, and guides *f*, substantially as shown and described.

3. In stencil-holders, the springs *g*, provided

with pins *h*, in combination with the clamping-plates A B, having end flanges, *c*, substantially as shown and described.

JOHN WILLIAM BENNETT.
